UNITED STATES PATENT OFFICE.

SAMUEL B. KAHN, OF CHICAGO, ILLINOIS.

CUFF-LINK.

1,369,926.

Specification of Letters Patent. Patented Mar. 1, 1921.

Application filed May 17, 1920. Serial No. 381,806.

To all whom it may concern:

Be it known that I, SAMUEL B. KAHN, a citizen of the United States, and resident of the city of Chicago, in the county of Cook and State of Illinois, have invented certain new and useful Improvements in Cuff-Links; and I do hereby declare that the following is a full, clear, and exact description of the same, reference being had to the accompanying drawings, and the numerals of reference marked thereon, which form a part of this specification.

My invention relates more particularly to a cuff button constructed of a pair of buttons and a resilient link connecting them. In the past when a person desired his initials put on his cuff buttons in the form of a monogram or otherwise it was necessary to have them cut thereupon by an engraver. This would require a great deal of trouble, time, and expense. To overcome this objection I have found it desirable to provide a stock of buttons upon which letters involving the entire alphabet are stamped or otherwise secured.

It is therefore an object of my invention to provide a novel form of link to which any selected buttons may be attached.

Other and further objects and advantages will be apparent from the drawings and specification.

On the drawings—

Figure 1 represents a perspective view of a hand having a cuff thereon supplied with a pair of cuff buttons involving my invention.

Fig. 2 is an elevational view of my improved cuff buttons.

Fig. 3 shows the end face of a button with a Japanese letter H stamped therein.

Fig. 4 is an end view of a detached button.

As shown on the drawings—

Referring now more specifically to the drawings, in which similar reference numerals denote the same features in the different views, reference numerals 1 and 2 denote a

pair of buttons having letters thereon representing the initials of a person's name, the buttons having been selected according to a desired design with the proper initials thereon. Buttons 1 and 2 are linked together by a resilient link 3. This link has a pair of eyes 8 in which rings 4 on the buttons are secured. These buttons are inserted through a slit 7 and snapped through the restricted neck 6. The material from which link 3 is made is sufficiently resilient to provide for this manner of assembly.

It will accordingly be seen that I have devised a novel means whereby persons may at once secure a set of cuff buttons of any selected design and having the proper letters already thereon to constitute the initials of their name. By using Japanese letters, I secure a neat, artistic effect and further, these buttons can be readily made by a cheap stamping process, after the dies have been made.

I am aware that numerous details of construction may be varied through a wide range without departing from the principles of this invention, and I therefore do not purpose limiting the patent granted otherwise than necessitated by the prior art.

I claim as my invention—
1. A connecting link for cuff buttons comprising a resilient member having a slit and a pair of eyelets defined by restricted necks, the cuff buttons being adapted to be snapped through said slit and through said restricted necks.

2. A connecting link for cuff buttons comprising a member having eyelets defined by restricted necks through which the buttons are adapted to be snapped into said eyelets.

In testimony whereof I have hereunto subscribed my name in the presence of a subscribing witness.

SAMUEL B. KAHN.
